UNITED STATES PATENT OFFICE.

PAUL OLUFF POULSON, OF BRIGHAM, UTAH.

ROTARY ENGINE.

No. 884,952.

Specification of Letters Patent. Patented April 14, 1908.

Application filed September 21, 1907. Serial No. 393,999.

To all whom it may concern:

Be it known that I, PAUL OLUFF POULSON, a citizen of the United States, and a resident of Brigham city, in the county of Boxelder and State of Utah, have invented a new and Improved Rotary Engine, of which the following is a full, clear, and exact description.

This invention relates to rotary engines, and the object of the invention is to produce an engine of this class which is simple in construction, and which will operate efficiently and economically in steam consumption.

A further object of the invention is to provide a construction whereby the steam which is projected upon the rotary member will be thrown back into steam pockets in the casing, so that the steam in these pockets can flow later onto the rotary member so as to accelerate its velocity.

20 The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a vertical transverse section 30 through an engine constructed according to my invention; Fig. 2 is a vertical longitudinal section of the engine; Fig. 3 is a vertical section similar to Fig. 1, but taken at another point, the wheel or rotor being shown 35 partly in elevation and partly in section; Fig. 4 is a section on the line 4—4 of Fig. 1, and passing through the steam ports and pockets; and Fig. 5 is a section on the line 5—5 of Fig. 1 and illustrating the arrangement of the exhaust.

Referring more particularly to the parts, 1 represents the case or frame of the engine, the upper portion of which is formed into a barrel or cylinder 2. Within this barrel a 45 piston drum or rotor 3 is rotatably mounted, the same being carried upon a suitable shaft 4 mounted in the case as indicated. The outer face of this drum is formed with a plurality of buckets 5. Each of these buckets 50 comprises a central passage 6 and side passages 7 disposed equidistant therefrom, said side passages being connected with each other and with the middle passage by a cross passage 8. The cross passage 8 is disposed 55 forwardly with respect to the direction of rotation, and the passage 6 comes to the surface

of the drum at a port 9; the passages 7 come to the surface in ports 10. These ports 9 and 10 are in alinement with each other as shown. In addition to this, there is a forwardly disposed port 11 which is in alinement with the port 9 and which communicates with its forward end as shown. At diametrically opposite points on the cylinder inlet ports 12 and 13 are provided, the inlet port 12 being disposed above, as shown. These ports 12 and 13 are inclined nearly tangentially to the drum and project in the direction of rotation; that is, the steam flowing in through the ports would flow in the general direction in which the rotation of the adjacent surface of the drum takes place. The ports 12 and 13 are formed into nipples to receive pipe connections 14 which bring in the live steam. On each side of the inlet ports 15 75 12 and 13, steam pockets 15 are formed, and these are of cylindrical form and extend substantially parallel with the inlet ports 12 and 13. This arrangement is clearly illustrated in the upper part of Fig. 2. The inlet ports 16 80 12 and 13 are in alinement with the ports 9 and 11 of the steam drum, and the steam pockets 15 are in alinement with the ports 10. In addition to the steam pockets 15 which are arranged at each side of the inlet ports 12 and 13, similar pockets 16 are arranged in pairs throughout the entire circumference of the cylinder. These pockets 16 are also in alinement with the ports 10. In addition to this, just to the rear of the inlet 17 85 ports 12 and 13 with respect to the direction of rotation, exhaust ports 17 are provided, to which suitable exhaust pipe connections 18 are attached. The live steam is admitted through the ports 12 and 13, and as the ports 19 90 pass under them, the steam projects itself through the ports 11 into the cross passages 8, in which it flows laterally and then rearwardly in the passages 7. In this way an impulse is given in a forward direction to the 100 rotating drum. As the buckets advance, the ports 10 pass under the pockets 15 or 16, and a portion of the steam which they contain flows rearwardly into these pockets. In this way, after the engine has been running a 105 short time, the pockets 15 and 16 become charged with steam under pressure. As the buckets pass under the pockets, this pressure exerts itself upon the buckets, and increases the velocity of rotation of the drum. The 110 pockets which are nearest to the inlet ports will have the highest intermediate pressure,

2 while the pockets nearest to the exhaust will have a lower pressure. In this way the action of the engine may be considered to resemble that of a compound engine, as the 5 pressure of the active steam drops by stages.

I provide seven of the buckets 5 in the rotor or drum spaced equidistant, and six of the reaction ports or pockets 16 in the cylinder, also spaced equidistant. By this ar- 10 rangement the buckets come successively in different phases or positions with relation to the pockets, and the impelling action of the steam becomes practically continuous. In addition to this, the admission ports are 15 placed diametrically opposite to each other so that it is impossible for the rotor to stop on a dead center.

Having thus described my invention, I claim as new and desire to secure by Letters 20 Patent:

1. A rotary engine having a cylinder with alining inlet ports formed in the wall there- 25 of, a drum rotatably mounted insaid cylinder and having buckets formed near the surface thereof, said buckets having ports alining with said inlet ports, and laterally disposed

passages with side ports opening upon the surface of said drum, and a plurality of steam pockets formed around the wall of said cylinder in alinement with said last ports, and 30 adapted to receive steam or give steam to said buckets.

2. A rotary engine having a cylinder with diametrically oppositely disposed inlet ports inclined toward a tangential line, a drum ro- 35 tatably mounted in said cylinder and having buckets in the outer wall thereof, said buckets having central passages disposed in aline- 40 ment with said inlet ports, and side passages descending laterally and rearwardly, said side passages having ports coming out upon the surface of said drum, said cylinder having a plurality of inclined pockets in aline- 45 ment with said last ports and adapted to receive steam or give steam thereto.

In testimony whereof I have signed my name to this specification in the presence of two subscribing witnesses.

PAUL OLUFF POULSON.
